UNITED STATES PATENT OFFICE

JAMES K. HEYMER, OF MINNEAPOLIS, MINNESOTA, ASSIGNOR TO CHRISTINE M. WARREN, GUARDIAN OF CLIDE W. WARREN, DOING BUSINESS AS WARREN SHADE COMPANY, OF MINNEAPOLIS, MINNESOTA

SUPPORTING MEANS FOR VENETIAN BLINDS

Application filed November 12, 1930. Serial No. 495,160.

This invention relates to a bracket for Venetian blinds.

It is desirable that certain types of shades, such, for example, as Venetian blinds, be detachably supported when they are in use, in order that said shades or Venetian blinds can be readily and easily removed from their supports to be cleaned or repaired, and just as readily and easily be again assembled with 10 their supports.

It is the general object of the present invention to provide brackets of novel and improved type for removably supporting a Venetian blind, or other shade, as, for example, within a window or similar opening.

A more specific object is to provide a bracket for a Venetian blind which will include supporting and supported elements of novel and improved construction and adapted to be detachably assembled together in novel and improved manner.

With the above objects in view, as well as others which will appear as the specification proceeds, the invention comprises the construction, arrangement and combination of parts as now to be fully described and as hereinafter to be specifically claimed.

In the accompanying drawings forming a part of this specification, and wherein like reference characters represent similar parts throughout the several views,

Fig. 1 is an elevational view of the upper portion of a window frame having a Venetian blind removably supported therein by brackets each made according to the invention;

Fig. 2 is an enlarged sectional view, taken on line 2—2 in Fig. 1, detailing features of the novel bracket;

Fig. 3 is an enlarged elevational view, taken on line 3—3 in Fig. 1, detailing the supporting element of the bracket at the left side of the disclosure of Fig. 1;

Fig. 4 is an enlarged view, partially in end elevation and partially in vertical section, of the Venetian blind removed from the window frame; and

Fig. 5 is a detail view, taken substantially on line 5—5 in Fig. 1 and partially broken 50 away.

With respect to the drawings and the numerals of reference thereon, 10 represents the upper cross member of a frame also including vertical side members 11 and 12 and providing an opening, such as a window opening, and 13 designates, generally, a Venetian blind adapted to be removably inserted in the opening of said frame.

The Venetian blind 13 consists of a horizontal supported or lifting member 14 carrying spaced apart suspension brackets 15 removably or otherwise supporting a reel 16 which carries spaced apart vertical tapes 17 themselves supporting spaced apart horizontal slats 18, all in any well known or preferred manner. The Venetian blind also includes the usual adjustment and lifting cords, designated 19 and 20, respectively. The cords 20 desirably travel over small pulleys 21 suitably arranged in the supported or lifting member 14. The cord 19 rides over a pulley in the member 14 and is looped around the reel 16.

The construction includes a supporting bracket arranged at each end of the supported or lifting member 14 and detachably mounting the Venetian blind within the open space of the frame. The supporting brackets for the Venetian blind are approximately duplicates, the only difference between said supporting brackets being that one is right and the other is left.

As shown, each frame side member 11, 12 suitably carries a supporting bracket element indicated 22 which may be secured to the corresponding frame member in any convenient manner as by screws entering holes in the bracket and screwed into the frame member or into structure adjacent said frame member. Each supporting bracket element 22 includes a vertical body portion attached to a side frame member 11 or 12, and having a horizontal ledge or ears 23 extending inwardly of the frame, the ledges or ears 23 of the different elements 22 lying in the same horizontal plane and being disposed directly opposite each other. At the rear of each element 22 is an upwardly extending stop element 24 which is integral with the rear ear 23. The ledges or ears 23 are arranged ad-

5 jacent the top member 10 of the frame, but are spaced therefrom a distance a trifle greater than the measurement representing the thickness of the supported or lifting member 14 of the Venetian blind.

As very clearly shown, the supported or lifting member 14 carries supported bracket elements 25 attached to the lower surface of said member 14, including an element 25 ar-

- 10 ranged adjacent each end of said supported or lifting member 14. In the disclosure as made, each element 25 is attached to the member 14 by screws 26 which also attach the brackets 15 to said member 14, and each ele-
15 ment 25 includes a body portion arranged in contiguous relation to the lower surface of the member 14 and an offset extension, or exten-
20 sions, projecting outwardly of the mem-
ber 14 and arranged parallel therewith in spaced relation thereto. Preferably, the off-
25 set extension, or extensions, of each element 25 consists of spaced apart ears 27 constructed and arranged in about the manner as illus-
trated.

- 25 When the Venetian blind is in use, the supported or lifting member 14 rests upon the ledges or ears 23 of the supporting bracket elements 22 adjacent the opposite sides of said Venetian blind in close proximity to 30 the side frame members and in the space between said ledges or ears 23 and the top frame member 10. Said member 14 is associated with said ledges or ears 23 by placing the member 14 adjacent the front edges of the ledges or ears 23 and sliding said member 14 rearwardly over said ledges or ears with the ears 27 disposed beneath and in contiguous relation to said ledges or ears 23. The mem-
35 ber 14 is pushed rearwardly until the back surface thereof engages the stops 24 of the different supporting bracket elements 22, as will be understood.

- 35 The forward face of the member 14 pivotally supports locking elements or clips 28, including an element or clip 28 arranged adjacent each end of said member 14. As disclosed, each locking element or clip 28 is pivotally attached to the member 14 by means of a screw 29. Forward portions of the 40 ledges or ears 23 of the supporting bracket elements 22 include slots 30, one in each element 22, adapted to be in alignment with the forward face of said member 14 when the rearward face of said member is in engagement with the stops 24, said slots being ar-
45 ranged to be entered by the locking elements or clips 28 when swung downwardly, as more clearly shown at the left side of Fig. 1 and in Figs. 2 and 3.

- 50 The arrangement is such that when the Venetian blind is supported by brackets 22, ears 23 are located between the ears 27 and the bottom of member 14, and any vertical and longitudinal or endwise movement of the 55 member 14 is thus prevented. When the

locking elements or clips 28 are positioned in the slots 30, said elements or clips and the stops 24 cooperate to prevent lateral or side-
60 wise movement of said member 14. Thus, it will be seen, the supported or lifting mem-
ber 14, which carries the remaining elements of the Venetian blind, is securely and firmly supported within the opening of the carrying frame therefor.

65 It will be evident that the supported or lift-
ing member 14, together with the remainder of the Venetian blind supported by said mem-
ber, can be readily and easily removed from the frame by first releasing the locking ele-
70 ments or clips 28 from the slots 30 and then drawing said member 14 forwardly to cause it and the ears 27 to slide over the ledges or ears 23 of the supporting bracket elements 22. The Venetian blind when removed can be cleaned, repaired, or otherwise attended to,
75 and can readily be replaced in the frame in the very simple manner as already set forth.

80 From the above description it is seen that applicant has provided a very simple and ef-
ficient bracket structure, and one which can be easily and quickly manipulated both to as-
85 semble a Venetian blind or other shade with a support therefor, and to disassemble said blind or shade from said support.

85 It will, of course, be understood that va-
rious changes may be made in the form, de-
tails, arrangement and proportions of the parts, without departing from the scope of applicant's invention which, generally stat-
ed, consists in a device capable of carrying 90 out the objects above set forth, and in the novel parts and combinations of parts dis-
closed and defined in the appended claims, the illustration and description herein being 95 merely illustrative and intended in no way 100 in a limiting sense.

105 What I claim is:—

110 1. In combination, a supporting element including a ledge, a member having an end portion adapted to rest upon and be slidable upon said ledge, and a locking element movable with said member and arranged to engage said supporting element.

115 2. In combination, a supporting element including a ledge, a member having an end portion adapted to rest upon and be slidable upon said ledge, an element supported by said member adapted to lie beneath said ledge in close proximity thereto, and a locking ele-
120 ment movable with said member and adapted to engage said supporting element to fasten said member in fixed relation to said support-
ing element.

125 3. In combination, a supporting element including a ledge, a member having an end portion adapted to rest upon said ledge, an element upon said member providing a slot adapted to slide upon said ledge, a stop at a rearward portion of said ledge for limiting movement of said member rearwardly of said 130

- ledge, and a locking element movable with said member and adapted to engage said supporting element to fix said member upon said ledge and in contiguous relation to said stop. 5
4. In combination, a supporting element including a portion adapted to be attached upon a structure and a ledge extending from said structure, a member having an end portion adapted to rest upon said ledge, an element providing, together with said member, a horizontal slot, said member adapted to slide upon said ledge rearwardly and forwardly thereof, a stop at a rearward portion of said ledge for limiting movement of said member rearwardly of said ledge, and a locking element upon said member and adapted to removably engage said supporting element to fasten said member against lateral movement upon said ledge. 10
5. In combination, a supporting element including a portion adapted to be attached upon a structure and a ledge extending from said structure, a member having an end portion adapted to rest upon said ledge, an element providing, together with said member, a horizontal slot, said member adapted to slide upon said ledge rearwardly and forwardly thereof, an upstanding stop integral with a rearward portion of said supporting element 15 for limiting movement of said member rearwardly of said ledge, and a locking element pivoted upon a forward surface of said member and adapted to removably enter a slot in said ledge alining with said forward surface to fasten said member upon said ledge. 20
6. In combination, a supporting element including a portion adapted to be attached upon a structure and a substantially horizontal portion extending from said structure, a member including a slot receiving said horizontal portion, said member adapted to slide upon said horizontal portion rearwardly and forwardly thereof, a stop for limiting movement of said member rearwardly of said horizontal portion, and a locking element for fastening said member upon said horizontal portion. 25
7. In combination, a supporting bracket including a portion adapted to be attached upon a structure and a substantially horizontal portion extending from said structure, a member including a slot receiving said horizontal portion, said member adapted to slide upon said horizontal portion rearwardly and forwardly thereof, an upstanding stop integral with a rearward part of said horizontal portion for limiting movement of said member rearwardly upon said horizontal portion, and a locking element secured upon said member and adapted to removably enter a slot in said horizontal portion to fasten said member against lateral movement upon said horizontal portion. 30
8. In combination, supporting brackets including portions adapted to be attached to a structure and substantially horizontal portions extending toward each other, said horizontal portions being in spaced relation, a member including slots adjacent its opposite ends receiving said horizontal portions, said member adapted to slide upon said horizontal portions rearwardly and forwardly thereof, stops for limiting movement of said member rearwardly of said horizontal portions, and locking elements for fastening said member upon said horizontal portions. 35
9. In combination, supporting brackets including portions adapted to be attached to a structure and substantially horizontal portions extending toward each other, said horizontal portions being in spaced relation, a member including slots adjacent its opposite ends receiving said horizontal portions, said member adapted to slide upon said horizontal portions rearwardly and forwardly thereof, said horizontal portions terminating adjacent the bases of said slots, an upstanding stop integral with a rearward part of each horizontal portion for limiting movement of said member rearwardly upon said horizontal portions, and locking elements secured upon said member and adapted to enter slots in said horizontal portions to fasten said member against lateral movement secured upon said horizontal portions. 40
10. A bracket for a Venetian blind having holes therein for attachment to a side member, apertured lugs at its rear portion for attachment to a vertical member, laterally projecting lugs at its top forming a ledge, a stop means at the rear of said ledge and a slot at the front of said ledge for receiving a locking member. 45
11. A pair of brackets for a Venetian blind including one bracket having means for receiving attaching members, a ledge at the top of said bracket with a stop means thereon and another bracket having an offset end adapted to be secured to a supporting bar of said blind and forming therewith a slot to receive said ledge of said first mentioned bracket. 50
